UNITED STATES PATENT OFFICE.

WALTER PHILLIPS, OF COVENTRY, ENGLAND.

DESIGN FOR A RUBBER TIRE FOR WHEELS.

SPECIFICATION forming part of Design No. 20,824, dated June 9, 1891.

Application filed December 31, 1890, Serial No. 376,423. Term of patent 7 years. Registered in England August 13, 1890, No. 154,358.

To all whom it may concern:

Be it known that I, WALTER PHILLIPS, manager to the Rudge Cycle Company, Limited, a subject of the Queen of Great Britain, 5 residing at Coventry, in the county of Warwick, England, have invented and produced a new and original Design for Hollow India-Rubber Tires for Wheels, of which the following is a specification, reference being had to the accompanying drawings, forming part thereof.

The drawing represents a cross-section of an india-rubber tire formed in accordance with the present design.

15 *a* is the outer or wearing face of the tire, which is intended to run upon the road. *b* is the inner face of the tire which is intended to fit into and be secured to the rim or felly of the wheel, and *c* is the hollow or bore. The inner 20 face *b* of the tire is contracted to fit the rim or felly, thus forming shoulders *d* to abut upon the rim and take the wear at that point.]

By forming india-rubber tires of the shape or design hereinbefore shown and described a more extended bearing-surface is obtained 25 by the employment of a given quantity of rubber than would be the case if the same quantity were made into a tire of the ordinary shape or design, while at the same time the liability of the tire to be cut by the edges 30 of the rim or felly is greatly reduced.

What I claim is—

The design for a hollow india-rubber tire for wheels, comprising a broad wearing or outer face *a* and a contracted inner face *b*, 35 connected by curves of large radius, forming shoulders *d*, as set forth.

WALTER PHILLIPS.
